UNITED STATES PATENT OFFICE

2,092,863

RAILWAY TRAFFIC CONTROLLING
APPARATUS

Harry C. Vantassel, Pittsburgh, Pa., assignor to
The Union Switch & Signal Company, Swiss-
vale, Pa., a corporation of Pennsylvania

Application August 2, 1930, Serial No. 472,612
Renewed September 3, 1932

13 Claims. (Cl. 246—3)

My invention relates to railway traffic controlling apparatus, and particularly to apparatus comprising a railway track switch and a signal directing traffic movements over the switch.

5 More particularly, my invention relates to the approach locking of a switch when a train enters a track section adjacent the signal while the signal is displaying a "proceed" indication. One object of my invention is to prevent the release 10 of the switch locking mechanism, by a momentary release of the track relay for the section including the switch, after a train has entered the approach section while a clear indication was being displayed by the signal.

15 The system and apparatus herein disclosed is an improvement upon that disclosed and claimed in a co-pending application, Serial No. 423,347, filed Jan. 25, 1930, by John M. Pelikan for Railway traffic controlling apparatus.

20 I will describe one form of apparatus embodying my invention, and will then point out the novel features thereof in claims.

25 The accompanying drawing is a diagrammatic view showing one form of apparatus embodying my invention.

Referring to the drawing, the reference characters 1 and 1^a designate the track rails of a stretch of railway track X which is connected by a switch F with a siding or spur track Y , and 30 which is divided by insulated joints 2 into sections A — B , B — C and C — D . Sections A — B and C — D will be hereinafter referred to as approach sections and section B — C , in which the switch F is located, will be referred to as a detector section. Each of these track sections is provided 35 with a track circuit including a battery 3 , connected across the rails adjacent one end of the section, and a track relay, designated by the reference character R with a distinguishing exponent, connected across the rails adjacent the other end of the section.

Traffic moving from left to right, as shown in the drawing, over tracks X and Y or over track X only is governed by signals S^2 and S^1 , respectively, while traffic moving in an opposite direction over these tracks is governed by signals S^4 and S^3 , respectively.

The switch F is moved between normal and reverse positions by a suitable operating mechanism M which is controlled from a remote point, such, for example, as a despatcher's office, through the medium of a polarized relay W . The relay W is controlled in part by a manually operable pole-changing device U , located in the despatcher's office, and in part by an actuator

relay T which is in turn controlled by an induction device or actuator 4 located in the trackway X adjacent the switch F .

The actuator 4 may be of any suitable type such, for example, as that shown and described in the copending application of Paul N. Bossart, Serial No. 442,991, filed April 9, 1930. The actuator 4 is a magnetic bridge structure, comprising two core members 5 and 6 separated by air gaps 7 and arranged between the rails 1 and 1^a of the track X . The core member 5 is provided with a primary winding 8 which is connected with terminals x and o of a source of alternating current not shown, and the core member 6 is provided with a secondary winding 9 which is connected with the terminals of the relay T . Normally, that is to say when there is no train over the actuator 4 , alternating current is induced in the secondary 9 of sufficient magnitude to operate the relay T , but when a train passes over the actuator the magnetizable parts of the train, such as the wheels and axles, will shunt a portion of the flux linking the core members 5 and 6 and will thus sufficiently decrease the electromotive force induced in the secondary 9 to cause the relay T to open its contact 12 .

Operated in conjunction with switch F is a pole-changing device P which controls the operation of a polarized switch indication relay G . The relay G controls, in part, relays H^1 and H^2 which control the signals S^1 and S^2 , respectively, for eastbound traffic, and also controls, in part, relays H^3 and H^4 which control the signals S^3 and S^4 , respectively, for westbound traffic. The relays H^1 and H^2 are also controlled in part, by a first master signal control relay K^1 which is controlled from the same remote point as relay W , by means not shown in the drawing, and the relays H^3 and H^4 are also controlled, in part, by a second master signal control relay K^2 which is also controlled from such remote point.

A first switch locking relay N^1 is controlled, in part, by the relays H^1 and H^2 , and a second switch locking relay N^2 is controlled, in part, by the relays H^3 and H^4 . The relays N^1 and N^2 are at times also controlled, in part, by a time element relay L having a slow pick-up and which is itself controlled by the relays H^1 and H^2 and by the relays H^3 and H^4 in a manner herein-after to be described.

With all parts of the apparatus in the normal condition, shown in the drawing, the switch F occupies its normal position, the track sections A — B , B — C and C — D are unoccupied, the sig-

nals S^1 , S^2 , S^3 and S^4 are all displaying "stop" indications, and the track relays R^1 , R^2 and R^3 and also the actuator relay T are all energized. Under these conditions, the relay W is energized by current of what I will term "normal polarity" which traverses a circuit passing from a battery 10 , through normal contact 11 of pole-changing device U , winding of polar relay W , front contact 12 of actuator relay T , front contact 13 of track relay R^2 , front contact 14 of relay N^2 , front contact 15 of relay N^1 , and normal contact 16 of pole-changing device U back to battery 10 . The energization of relay W completes a circuit passing from terminal c of a source of direct current, through normal contact 17 of relay W , switch actuating mechanism M , and normal contact 18 of relay W to the other terminal d of the same source of current. This causes the switch actuating mechanism M to maintain the switch F in its normal position.

If, however, the despatcher desires to reverse the switch F , he will move the pole-changing device U so as to close its reverse contacts 11 and 16 , thereby reversing the polarity of the current energizing the polarized relay W . This causes relay W to close its reverse contacts 17 and 18 and thereby reverse the polarity of the current energizing the switch actuating mechanism M , which causes mechanism M to move the switch F to its reverse position.

When the switch F occupies its normal position, the pole-changing device P is in the position shown in the drawing. This causes the energization of polarized relay G by current of normal polarity which traverses a circuit passing from terminal c , through normal contact 19 of pole-changing device P , winding of relay G , and contact 20 of pole-changing device P to terminal d . If, however, the switch F is moved to its reverse position, the pole-changing device P closes its reverse contacts 19 and 20 , thereby reversing the polarity of the current energizing the relay G .

The switch locking relays N^1 and N^2 are both energized when the apparatus is in its normal condition. The relay N^1 is energized by a pick-up circuit passing from terminal c , through back contact 21 of relay H^1 , back contact 22 of relay H^2 , front contact 23 of track relay R^1 , and winding of relay N^1 to terminal d . Relay N^1 is also energized by a stick circuit passing from terminal c , through back contact 21 of relay H^1 , back contact 22 of relay H^2 , front contact 24 of relay N^1 , and winding of relay N^1 to terminal d . The relay N^2 is energized by a pick-up circuit passing from terminal c , through back contact 25 of relay H^3 , back contact 26 of relay H^4 , front contact 27 of track relay R^3 , contact 28 of pole-changing device P , and winding of relay N^2 to terminal d . Relay N^2 is also energized by a stick circuit passing from terminal c , through back contact 25 of relay H^3 , back contact 26 of relay H^4 , front contact 29 of relay N^2 , and winding of relay N^2 to terminal d .

I will now assume that the despatcher desires to route an eastbound train over the track X with switch F in its normal position. He accordingly causes the energization of relay K^1 by virtue of a circuit controlled from the despatcher's office, and thus causes the energization of relay H^1 by a circuit passing from terminal c , through back contact 30 of relay K^2 , normal polar contact 31 and neutral contact 32 of polarized relay G , back contact 33 of time element relay L , front contact 34 of track relay R^2 , front contact 35

of actuator relay T , neutral contact 36 and normal polar contact 37 of polarized relay G , front contact 38 of relay K^1 , front contact 39 of track relay R^3 , and winding of relay H^1 to terminal d . The energization of relay H^1 opens its back contact 21 , thereby interrupting the pick-up and stick circuits previously traced through this contact for relay N^1 , and so causing relay N^1 to open its front contacts 15 and 24 and to close its back contact 24 . The opening of front contact 15 of relay N^1 interrupts the circuit previously traced through this contact by which the relay W was energized, thereby deenergizing relay W and so preventing reversal of polarity of the current supplied to switch actuating mechanism M . The energization of relay H^1 completes a circuit passing from terminal c , through front contact 40 of relay H^1 , and operating mechanism of signal S^1 to terminal d , and so causes this signal to display a "proceed" indication to an eastbound train for the track X .

The train, upon entering section $A-B$, causes the deenergization of track relay R^1 , contact 23 of which thereupon opens in the pick-up circuit traced for relay N^1 , which is, however, already deenergized on account of the opening of contact 21 of relay H^1 .

The train next enters section $B-C$, causing the deenergization of track relay R^2 which then opens its front contacts 13 and 34 . The opening of front contact 13 of this relay forms another break in the circuit previously traced for relay W , and the opening of front contact 34 interrupts the circuit for relay H^1 . The deenergization of relay H^1 opens its front contact 40 , thereby interrupting the circuit previously traced through this contact and causing the signal S^1 to again display the "stop" indication. The deenergization of relay H^1 closes back contact 21 of this relay and so establishes a circuit passing from terminal c , through back contact 21 of relay H^1 , back contact 22 of relay H^2 , back contact 24 of relay N^1 , and winding of time element relay L to terminal d . By reason of the fact that relay L has a slow pick-up, it does not immediately close its front contacts and, therefore, if the train proceeds at its normal rate of speed, the circuits controlled by this relay will remain unaffected, as will be hereinafter described.

The train, upon moving over the actuator A , causes the deenergization of the actuator relay T . This relay then opens its front contact 12 , thereby breaking the circuit for relay W , previously traced through this contact, at still another point. The deenergization of actuator relay T establishes a circuit passing from terminal c , through back contact 21 of relay H^1 , back contact 22 of relay H^2 , back contact 41 of relay T , back contact 42 of track relay R^2 , and winding of relay N^1 to terminal d , thereby causing the reenergization of relay N^1 . This causes back contact 24 of relay N^1 to interrupt the circuit for relay L , previously traced through this contact. If the train is moving at a normal rate of speed, this interruption of the circuit for relay L occurs before there has been time for contacts 51 and 52 to close. The energization of relay N^1 closes front contact 24 which reestablishes the stick circuit previously traced for this relay. The deenergization of actuator relay T also establishes a second energizing circuit for relay N^2 , passing from terminal c , through back contact 25 of relay H^3 , back contact 26 of relay H^4 , back contact 43 of track relay R^3 , back contact 44 of actuator relay T , and winding of relay N^2 to terminal d .

- When the rear end of the train departs entirely from section A—B, track relay R¹ again becomes energized and closes its front contact 23 which reestablishes the first pick-up circuit traced for relay N¹.
5. As soon as the rear end of the train clears the actuator 4, the relay T again becomes energized and closes its front contacts 12 and 35, but inasmuch as front contacts 13 and 34 of track relay R² are both still open, the circuits for the relays W and H¹, respectively, remain open. The energization of relay T also opens back contacts 41 and 44 of this relay, thereby interrupting the second pick-up circuits for relays N¹ and N², respectively, previously traced.
10. The train, upon entering section C—D, causes the deenergization of track relay R³. This relay then opens its front contact 27, interrupting the first pick-up circuit for relay N², but relay N² remains energized by virtue of its stick circuit previously traced through its front contact 29.
15. The rear portion of the train now leaves section B—C, and so permits the track relay R² to again become energized and open its back contacts 42 and 43 and close its front contacts 13 and 34. Assuming that the dispatcher restored relay K¹ to the deenergized condition before the train left section B—C, the circuit for relay W will now be again completed by the closing of contact 13 of relay R². The opening of contacts 42 and 43 of relay R² breaks the second pick-up circuits for relays N¹ and N², respectively.
20. As soon as the train departs entirely from section C—D, the track relay R³ again becomes energized and closes its front contacts 27 and 39, thereby completing restoration of the apparatus to its original normal condition.
- I will now assume that the dispatcher desires to route an eastbound train onto the track Y. In such event, he shifts the position of the pole-changing device U so as to close its reverse contacts 11 and 16. This reverses the polarity of the current energizing the polarized relay W and causes it to close its reverse polar contacts 17 and 18. The closing of these contacts also reverses the polarity of the current energizing the switch actuating mechanism M, and so causes it to move the switch F to its reverse position. When the switch F is thus operated, it shifts the position 50 of the pole-changing device P from the position shown in the drawing to a position in which it opens its contact 28 and its normal contacts 19 and 20, and closes its reverse contacts 19 and 20, thereby energizing the relay G by current of reverse polarity and causing this relay to close its reverse contacts 31 and 37. The opening of contact 28 breaks the first pick-up circuit for relay N² which, however, continues energized by its stick circuit.
55. If the dispatcher should now cause the relay K¹ to be energized, a circuit will be established, passing from terminal c, through back contact 45 of relay K², reverse polar contact 31 and neutral contact 32 of relay G, back contact 33 of relay L, front contact 34 of track relay R², front contact 35 of relay T, neutral contact 36 and reverse polar contact 37 of relay G, front contact 46 of relay K¹, and winding of relay H² to terminal d. The energization of relay H² establishes a circuit for signal S² passing from terminal c, through front contact 47 of relay H², and operating mechanism of signal S² to terminal d. The signal S² is thus caused to display a "proceed" indication for track Y. The energization of relay H² causes it to open its back contact 22, which
- interrupts both the pick-up and stick circuits for relay N¹ previously traced through this contact, thereby causing relay N¹ to open its front contact 15 and to close its back contact 24. The opening of front contact 15 of relay N¹ again interrupts the energizing circuit for relay W previously traced through this contact, and so prevents reversal of polarity of the current supplied to switch actuating mechanism M.
- If an eastbound train should now enter section A—B, track relay R¹ will become deenergized and open its front contact 23, and as soon as the train enters section B—C, the track relay R² will also become deenergized and open its front contact 34. The opening of contact 34 interrupts the circuit for relay H² previously traced through this contact, and so causes front contact 47 of relay H² to interrupt the circuit for signal S². This signal will, therefore, resume its normal "stop" position. As the train proceeds over tracks X and Y, the further operation of the apparatus is substantially the same as that described in connection with through traffic over track X.
- If the dispatcher, after having cleared signal S¹ for an eastbound train entering section A—B, subsequently decides to route the train from track X to track Y instead of over track X, he will deenergize relay K¹, thereby opening front contact 33 of this relay and interrupting the circuit for relay H¹. The deenergization of relay H¹ opens front contact 48 of this relay and hence also the circuit previously traced therethrough for signal S¹, thereby causing signal S¹ to return to its normal "stop" position. The deenergization of relay H¹ also closes back contact 21 of this relay, and establishes the circuit for time element relay L previously traced from terminal c, through this contact 21, back contact 22 of relay H², back contact 24 of relay N¹, and winding of relay L to terminal d. This causes the energization of relay L but this relay having a slow pick-up will not close its front contacts until after a predetermined time interval has elapsed. If the train has time to obey the signal S¹ and comes to a stop while it is still within section A—B, the relay L will close its contacts 51 and 52 at the expiration of a predetermined interval of time and complete a circuit for relay N¹ passing from terminal c, through back contact 21 of relay H¹, back contact 22 of relay H², front contact 51 of time element relay L, and winding of relay N¹ to terminal d. The energization of relay N¹ establishes the circuit previously traced for polarized relay W, and so permits the dispatcher to operate the switch F to its reverse position in the manner hereinbefore described.
- If, however, the train is travelling at too high a rate of speed to obey the "stop" indication of the signal S¹, it will enter section B—C and cause the deenergization of track relay R² before the time element relay L has had time to close its front contact 51. As a result, when the time interval for relay L elapses and this relay closes its front contact 51,—assuming that the train stops before reaching actuator 4,—the circuit for relay W will not, in this case, be established for the reason that front contact 13 of track relay R² is now open. This prevents the dispatcher from operating the switch immediately in front of the train, and confines the operation thereof to such time as the train occupies section A—B.
- I will now assume that with the switch in its normal position, a westbound train is approaching over the track X and that the dispatcher desires to admit such train into section B—C. To

do this, he first causes the energization of relay K² which then closes its front contact 30 and so establishes a circuit for relay H³ passing from terminal c, through back contact 38 of relay K¹, normal polar contact 37 and neutral contact 36 of relay G, front contact 35 of relay T, front contact 34 of track relay R², back contact 33 of relay L, neutral contact 32 and normal polar contact 31 of relay G, front contact 30 of relay K², front contact 48 of relay R¹, and winding of relay H³ to terminal d. The energization of relay H³ causes it to close its front contact 49 which establishes a circuit passing from terminal c, through front contact 49 of relay H³, and operating mechanism of signal S³ to terminal d, thereby causing this signal to display a "proceed" indication to the approaching westbound train. The energization of relay H³ also opens back contact 25 of this relay and so interrupts the circuits for relay N² previously traced through this contact and causes the deenergization of this relay. This causes relay N² to open its front contact 14 and to thus break the circuit for relay W previously traced through this contact. The switch F, therefore, is locked in its normal position in the manner hereinbefore described. As the train proceeds into section C—D and thence through the other sections, the operation of the apparatus is similar to that previously described for eastbound traffic.

If a westbound train is approaching on track Y and the despatcher desires to route such train over the switch F onto track X, he will first move the switch to its reverse position and then cause the energization of relay K². In this case, the energization of relay K² causes the energization of relay H⁴ by virtue of a circuit established from terminal c, through back contact 46 of relay K¹, reverse polar contact 37 and neutral contact 36 of relay G, front contact 35 of relay T, front contact 34 of relay R², back contact 33 of relay L, neutral contact 32 and reverse polar contact 31 of relay G, front contact 45 of relay K², and winding of relay H⁴ to terminal d. The energization of relay H⁴ establishes a circuit for signal S⁴ passing from terminal c, through a front contact 50 of relay H⁴, and operating mechanism of signal S⁴ to terminal d, which causes this signal to display a "proceed" indication to the westbound train approaching over track Y.

If the despatcher, after having cleared signal S³ for a westbound train entering section C—D, subsequently decides to admit a second westbound train onto track X from track Y ahead of the first mentioned train, he will deenergize relay K², thereby opening front contact 30 of this relay and thus interrupting the circuit for relay H³. The deenergization of relay H³ opens front contact 49 of this relay and the circuit previously traced therethrough for signal S³, thereby causing signal S³ to return to its normal "stop" position. The deenergization of relay H³ also closes back contact 25 of this relay and establishes a circuit for the time element relay L passing from terminal c, through back contact 25 of relay H³, back contact 26 of relay H⁴, back contact 29 of relay N², and winding of time element relay L to terminal d. This causes the energization of relay L but this relay, as has been pointed out, has a slow pick-up and hence does not close its front contacts immediately. If the train in section C—D has time to obey the signal S³ and comes to a stop before passing signal S³, relay L will close its contact 52 after a predetermined time interval has elapsed and will thereby complete a circuit

for relay N², passing from terminal c, through back contact 25 of relay H³, back contact 26 of relay H⁴, front contact 52 of time element relay L, and winding of relay N² to terminal d. The energization of relay N² establishes the circuit previously traced for relay W and thus permits the despatcher to operate the switch F to its reverse position.

If, however, the train on track X is traveling at a high rate of speed or for some other reason fails to obey the "stop" indication of signal S³, it will enter section B—C and cause the deenergization of track relay R² before the relay L has had time to close its front contacts. As a result, when relay L eventually picks up at the expiration of its time interval and closes its front contact 52, the circuit for relay W will not be established, for the reason that front contact 13 of track relay R² will be open. This prevents the despatcher from operating the switch F immediately in front of the train and insures that the train on track X shall stop before passing signal S³ if the switch F is to be operated for the train on track Y.

One feature of my invention is that the approach locking for the switch F will not be falsely released in the event of momentary release of the track relay R² or in the event of any other abnormal operation of this relay. This is due to the fact that when a train passes along the stretch of track shown in the drawing, relays N¹ and N² can become energized by the deenergization of relay R² only while a train is positioned over actuator 4.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, a switch associated with said section, a switch locking relay for controlling the operation of said switch, a time element relay for controlling the operation of said switch locking relay, manually controlled means for controlling the operation of said time element relay, and a magnetic bridge structure controlled by a train in said section for controlling said switch locking relay jointly with said time element relay.

2. In combination, a section of railway track, a switch associated with said section, a signal for controlling traffic movements over said switch, control means for said signal, a stick relay for controlling the operation of said switch, a magnetic bridge structure controlled by traffic conditions in said section, a pick-up circuit for said relay controlled by said bridge structure, and a stick circuit for said relay controlled by said signal control means.

3. In combination, a stretch of railway track, traffic governing means associated with said stretch, manually controllable means for controlling said traffic governing means, a track relay for controlling the operation of said manually controllable means, and an induction device located adjacent said stretch but insulated from the track rails and controllable by a train to prevent operation of said traffic governing means.

4. In combination, a section of railway track, a switch associated with said section, manually controllable means for controlling said switch, a track relay operable when a train enters said sec-

tion for controlling the operation of said manually controllable means, and a train-controlled induction device insulated from the track rails for preventing operation of said manually controllable means.

5. In combination, a section of railway track, traffic governing means located in said section, a track relay associated with said section, a second relay associated with said section, an induction device controllable by a train when and only when said train is in said section for controlling said second relay, a manually controlled relay for controlling the operation of said traffic governing means, and a circuit for said manually controlled relay including a contact of said track relay and a contact of said second relay.

6. In combination, a section of railway track, traffic governing means located in said section, a track relay associated with said section, a second relay associated with said section, an induction device controllable by a train when and only when said train is in said section for controlling the operation of said second relay, a manually controlled relay for controlling the operation of said traffic governing means, and a circuit for said manually controlled relay including a front contact of said track relay and a front contact of said second relay.

7. In combination, a section of railway track, traffic governing means located in said section, a track relay associated with said section, a second relay associated with said section, an induction device controllable by a train when and only when said train is in said section for controlling said second relay, a manually controlled relay for controlling the operation of said traffic governing means, and a circuit for said manually controlled relay controlled jointly by said track relay and said second relay.

8. In combination, a section of railway track, traffic governing means located in said section, a track relay associated with said section, a second relay associated with said section, an induction device controllable by a train when and only when said train is in said section for controlling said second relay, a manually controlled relay for controlling the operation of said traffic governing means, and a circuit for said manually controlled relay including a contact of said track relay and a contact of said second relay in series.

9. In combination, a section of railway track, a switch located in said section, a track relay associated with said section, a second relay associated with said section, a magnetic bridge structure for normally energizing said second relay and operable to deenergize said second relay when and only when a train is in said section, and means controlled by a front contact of said track relay and a front contact of said second relay for controlling said switch.

10. In combination, a section of railway track, a switch located in said section, a polarized relay for controlling the operation of said switch, a track relay associated with said section, a second relay associated with said section, a magnetic bridge structure operable by a train when and only when said train is in said section for controlling said second relay, a third relay, a slow-acting relay for controlling said third relay, and a circuit for said polarized relay including a contact of said track relay, a contact of said second relay, and a contact of said third relay.

11. In combination, a section of railway track, a switch located in said section, a polarized relay for controlling the operation of said switch, a pole-changing device for controlling said polarized relay, a track relay associated with said section, a second relay associated with said section, a magnetic bridge structure controllable by a train when and only when said train is in said section for controlling said second relay, a third relay, a signal, a manually controllable relay for controlling said signal, a circuit for said polarized relay including said pole-changing device, a contact of said third relay, a contact of said track relay and a contact of said second relay in series, and a slow-acting relay controlled by said manually controllable relay for delaying the operation of said third relay for a predetermined time interval after the operation of said manually controllable relay.

12. In combination, a section of railway track, traffic governing means located in said section, a track circuit having a normally energized track relay for said section, a second normally energized relay for said section, means independent of said track circuit for causing said second relay to be deenergized by a train in said section, a manually controlled relay, circuits including contacts of said manually controlled relay for controlling the operation of said traffic governing means, and a circuit for said manually controlled relay including a contact of said track relay and a contact of said second relay.

13. In combination, a section of railway track, traffic governing means located in said section, a track circuit having a normally energized track relay for said section, a second normally energized relay for said section, means independent of said track circuit for causing said second relay to be deenergized by a train in said section, a manually controlled relay, circuits including contacts of said manually controlled relay for controlling the operation of said traffic governing means, and a circuit for said manually controlled relay including a front contact of said track relay and a front contact of said second relay.

HARRY C. VANTASSEL
